ATTACHMENT FOR A CAN-TYPE ASH TRAY OR SIMILAR ARTICLE

Alec Thompson Miller, 4825 Chatham St., Vancouver,
British Columbia, Canada

Filed Mar. 16, 1964, Ser. No. 79,031

Term of patent 14 years

(Cl. D85—8)

FIGURE 1 is a perspective view of a combined cigarette rest and pipe holder attachment for a can type ash tray or similar article, showing my new design;

The partial showing of an ash tray in FIGURE 1 by means of dashed lines is for illustrative purposes only.

I claim:

The ornamental design for a combined cigarette rest and pipe holder attachment for a can-type ash tray or similar article, as shown and described.
